UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

FIREARM.

No. 807,745.

Specification of Letters Patent.

Patented Dec. 19, 1905.

Application filed November 13, 1903. Serial No. 181,032.

To all whom it may concern:

Be it known that I, THOMAS C. JOHNSON, of New Haven, in the county of New Haven and State of Connecticut, have invented a new and useful Improvement in Firearms; and I do hereby declare the following, when taken in connection with the accompanying drawings and the figures of reference marked thereon, to be a full, clear, and exact description of the same, and which said drawings constitute part of this specification, and represent, in—

Figure 1, a broken view, partly in side elevation and partly in vertical central section, of a gun provided with my invention; Fig. 2, a detached side view of one form of friction-brake which I may employ; Fig. 3, a view thereof in rear elevation.

My invention relates to an improvement in firearms, the object being to provide simple and effective means for reducing the shock of recoil in that class of firearms having non-recoiling as distinguished from recoiling barrels.

With these ends in view my invention consists in a firearm having certain details of construction and combinations of parts, as will be hereinafter described, and pointed out in the claims.

In the drawings I have shown my invention as applied to a gun provided with what is known as a "balanced" breech-block or breech-closure 2, which has a long forwardly-projecting balancing extension 3. This breech-block belongs to that class of breech-blocks which are not positively locked for the purpose of taking the shock of recoil, but which are made to contain a quantity of metal proportioned to the weight of the bullet and its velocity, so that the shock of recoil will be absorbed by the aggregate mass of the breech-block, which, in a sense, therefore, balances the recoil. For that reason breech-blocks of this type are called "balanced" breech-blocks to distinguish them from positively-locked breech-blocks, which are the more generally employed. Now in order to assist such a balanced breech-block to take the recoil I provide a friction-brake, which may take a variety of forms, according to the dictation of circumstances, but which in this particular case has taken the form of a conical friction-sleeve 4, split throughout its length by a slot 5, and having its expansibility further increased by slots 6, which do not extend

throughout its length. This sleeve is mounted 55 upon the forward end of a guide-rod 7, provided for guiding the balancing extension 3, located underneath the non-recoiling barrel 8 and rigidly secured at its rear end in a recoil-taking lug 9, depending from the rear end 60 thereof, as more fully shown and described in my prior patent, No. 720,698, granted February 17, 1903. The balancing extension 3 is formed with a long spring-chamber 10, receiving a breech-block-closing spring 11, which 65 encircles the said rod, which extends forward through the said chamber. At its forward end the said spring impinges against the rear end of the said friction-sleeve 4, which is located in a conical brake-chamber 12, forming 70 an extension of the forward end of the spring-chamber 10.

For manually opening the gun, which is necessary for the introduction of the first cartridge into the gun-barrel, this gun is furnished with a plunger 13, provided at its forward end with an operating-button 14, mounted in the fore-stock tip 15, adapted at its inner end to engage with a portion of the forward end of the balancing extension 3 and provided 75 with a spring 16, which pushes it forward into its normal position after its operation for manually opening the gun, all as fully described in my prior patent above referred to.

When the gun is fired and the breech-block 85 recoils, the tapering walls of the conical chamber 12 ride over the side walls of the sleeve 4 and compress the same and cause it to take a firm grip upon the guide-rod 7. In this connection it may be mentioned that the 90 sleeve is constructed so that it is slightly expanded when applied to the rod in the first place. The friction-sleeve is now "dragged," so to speak, rearward with the balancing-extension and over the rod 7 and materially 95 assists the balancing extension 3 in reducing the shock of recoil. It constitutes a steady drag on the breech-block and prevents the same from being thrown rearward with undue force. When the breech-block recoils, the 100 breech-block-closing spring 11 is placed under tension for returning the breech-block to its closed position, and it not only has to move the weight of the breech-block 2 and its balancing extension 3, but also must overcome 105 the friction of the sleeve 4 upon the rod 7 as the sleeve is pushed forward by the spring over the rod.

In view of the modifications which may obviously be made I would have it understood that I do not limit myself to the exact construction shown, but hold myself at liberty to make such departures therefrom as fairly fall within the spirit and scope of my invention.

Having fully described my invention, what I claim as new, and desire to secure by Letters Patent, is—

- 1. In an automatic firearm, the combination with a non-recoiling barrel, of a balanced breech-block having a forwardly-projecting extension formed with a spring-chamber and with a brake-chamber, a forwardly-projecting stationary rod extending into the said spring and brake-chambers, a breech-block-closing spring located in the said spring-chamber and encircling the said rod, and a friction-brake applied to the said rod and located in the said brake-chamber the walls of which engage with it and cause it to coact with the rod in retarding the opening movement of the breech-block at the time of recoil.
- 2. In an automatic firearm, the combination with a non-recoiling barrel, of a balanced breech-block having a forwardly-projecting extension formed with a spring-chamber and with a brake-chamber located at the forward end of the said spring-chamber, a forwardly-projecting stationary rod extending into the said chambers, a breech-block-closing spring located in the said spring-chamber and encircling the said rod, and a friction-brake applied to the said rod and located in the said brake-chamber the walls of which engage with it and cause it to coact with the rod in retarding the opening movement of the breech-block at the time of recoil.
- 3. In an automatic firearm, the combination with a non-recoiling barrel, of a balanced breech-block having a forwardly-projecting extension formed with a spring-chamber and with a conical brake-chamber, a forwardly-projecting stationary rod extending into the

said chambers, a breech-block-closing spring 45 located in the said spring-chamber and encircling the said rod, and a conical friction-brake applied to the said rod and located in the said brake-chamber the tapering walls of which engage with it and cause it to coact with the 50 rod in retarding the opening movement of the breech-block at the time of recoil.

4. In an automatic firearm, the combination with a non - recoiling barrel, of a balanced breech-block having a forwardly-projecting 55 extension formed with a spring-chamber and with a brake-chamber, a forwardly-projecting stationary rod extending into the said chambers and mounted at its rear end in a lug depending from the barrel, a breech-block-closing spring located in the said spring-chamber and encircling the said rod, and a friction-brake applied to the said rod and located in the said brake-chamber the walls of which engage with it and cause it to coact 60 with the said rod in retarding the opening movement of the breech-block at the time of recoil.

5. In an automatic firearm, the combination with a non-recoiling barrel having a depending recoil-taking lug, of a balanced breech-block having a forward extension, a stationary rod mounted in the said lug and extending forward into the said extension, a breech-block-closing spring located in the said extension and encircling the said rod, and a friction-brake mounted upon the said rod and operated by the said breech-block to retard the opening movement of the breech-block and thus reduce the shock of recoil. 75

In testimony whereof I have signed this specification in the presence of two subscribing witnesses.

THOMAS C. JOHNSON.
